TRAVELING-WAVE TUBE

Charles K. Birdsall and Lester M. Field, Los Angeles, Calif., assignors to Hughes Aircraft Company, Culver City, Calif., a corporation of Delaware

Application February 23, 1955, Serial No. 490,088

5 Claims. (Cl. 315—3.5)

This invention relates to microwave tubes and more particularly to the slow-wave structure of a traveling-wave tube.

Recent developments in high power traveling-wave tube construction involve the use of slotted, tubular, conductive slow-wave structures, one of which is disclosed in a copending application, Serial No. 450,987, filed August 19, 1954, by Charles K. Birdsall. Another copending application, Serial No. 456,682, filed September 17, 1954, of which the present application is a continuation-in-part, is directed to related slow-wave structures. These types of slow-wave structures have been employed in traveling-wave tube amplifiers to avoid self-oscillations due to backward wave type interaction within a band of frequencies normally constituted of centimeter wavelengths. A tubular slow-wave structure is thus employed to propagate an electromagnetic wave in the usual manner at a velocity substantially less than the velocity of light whereby an electron stream may be projected coaxially through the slow-wave structure at approximately the same velocity as that of the wave. Mutual interaction of the stream and the wave is consequently produced, the interaction causing the wave to "grow" or to be amplified. A complete collimation of the stream electrons is desirable to effect optimum interaction of the stream with the propagated wave; however, as many as one-tenth of the stream electrons generally collide with the slow-wave structure in a high power tube, such as that disclosed in the applications above referred to, and a convection current as large as one ampere may be produced in the slow-wave structure. The energy of the stream electrons impinging upon the slow-wave structure is turned into heat which must be removed. It is desirable to provide means to conduct this heat away from the slow-wave structure and which means does not change the slow-wave structure impedance over the operating frequency band.

Further, when a slow-wave structure constituted of a conventional conductive helix is employed, such a helix being desirable for low-power applications, backward wave self-oscillations may prohibit the operation of a traveling-wave tube as an amplifier within the backward wave self-oscillation band of frequencies.

An object of the invention is therefore to provide means for conducting heat from a traveling-wave tube slow-wave structure without producing a substantial change in the impedance of that structure over the operating frequency band of the tube.

Another object of the invention is to provide means for substantially suppressing backward-wave oscillations along a traveling-wave tube slow-wave structure without producing a substantial change in the impedance of that structure over the operating frequency band of the tube.

It is a further object of the invention to provide means for modifying the phase velocity frequency characteristic of the slow-wave structure of a traveling-wave tube to

2
control the bandwidth of operation and, at the same time, to increase the impedance of the structure.

By practicing the present invention a solution to the heat conduction problem in high-power tubes or a solution to the backward wave self-oscillation problem accompanying the use of a conductive helix may be obtained as well as the control over the bandwidth of operation. To this end, in accordance with the invention a plurality of relatively thin axially spaced conductors are connected radially from a slow-wave structure to a hollow, cylindrical, conductive envelope, the envelope being disposed concentrically about the slow-wave structure.

The novel features which are believed to be characteristic of the invention are set forth with particularity in the appended claims. The invention itself, however, both as to its organization and method of operation, together with additional objects and advantages of the invention, may be better understood when taken in connection with the accompanying drawings in which several embodiments of the invention are illustrated by way of example. It is to be expressly understood, however, that the drawings are for the purpose of illustration and description only, and are not intended as a definition of the limits of the invention.

Fig. 1 is a sectional view of a traveling-wave amplifier embodying the present invention;

Figs. 2 and 3 are sections along the lines 2—2 and 3—3, respectively, of Fig. 1;

Fig. 4 is a broken orthogonal view of the heat conducting and slow-wave structure of the amplifier of Fig. 1;

Fig. 5 is a broken orthogonal view of an alternative embodiment of the heat conducting and slow-wave structure of the amplifier of Fig. 1;

Figs. 6 and 7 are broken sectional views of another embodiment of the slow-wave structure of the present invention;

Figs. 8 and 9 are orthogonal broken-away views of still other embodiments of the heat conducting and slow-wave structure of the amplifier of Fig. 1; and

Fig. 10 is a broken plan view of a conventional slow-wave structure or conductive helix having periodic discontinuities provided along its length to provide the heat conducting structures of the present invention.

Referring to Fig. 1, a traveling-wave tube amplifier 10 is illustrated having a cylindrical, conductive, non-magnetic envelope 12 which may be made of copper. An electron gun 14 is sealed in the left extremity of the envelope, as viewed in Fig. 1. Electron gun 14 is employed to produce a stream of electrons and to direct it along the longitudinal axis of envelope 12.

A solenoid 16 is disposed concentrically about envelope 12 to provide an axial magnetic field along the electron stream path whereby the stream may be constrained along the complete length of the envelope. Such a field may be of the order of 600 to 1200 gauss. In order to produce the magnetic field, a direct current is maintained in solenoid 16 by means of a potential source 18.

A non-magnetic conductive cooling tank 19 having the shape of a double-walled hollow cylinder and which may also be made of copper is disposed concentrically between solenoid 16 and envelope 12. A liquid or gaseous coolant may thus be circulated through the tank to conduct heat away from both solenoid 16 and envelope 12.

Electron gun 14 essentially comprises a cathode cylinder 20, a heater 22, a focusing electrode 24, and an accelerating anode 26. Heater 22 is connected across a suitable source of potential 28, the negative side of the heater being connected to cathode 20. The negative side of source 28 is then connected to the negative terminal of a potential source 30, the positive side of which is connected to ground in order to maintain cathode 20 at

a potential of about 30,000 to 35,000 volts negative with respect to ground. Focusing electrode 24 has a frustoconical shape with an internal surface of revolution forming an angle of 67½ degrees with its axis of symmetry. Focusing electrode 24 is maintained at the same potential as cathode 20 by an appropriate connection thereto. Accelerating anode 26 is maintained at about 200 volts positive with respect to ground by a connection to a tap 32 on potential source 30.

A disc-shaped magnetic pole piece 33 and dielectric spacer 34 are disposed contiguously to a cylindrical appendage 27 of anode 26 to maintain the gun 14 in alignment with envelope 12. A glass stem 36 with integral leads 37 welded to the gun 14 and an anode lead 38 comprise the remaining supports of gun 14.

Within envelope 12, adjacent to and to the right of gun 14, as viewed in Fig. 1, slow-wave structure 40 is provided in electrical contact with and supported in part by a rectangular internal input waveguide segment 42 and a rectangular internal output waveguide segment 44. The slow-wave structure 40 and waveguide segments 42 and 44, which may consist of copper, are all maintained at ground potential by an electrical connection 45 from envelope 12 to ground. As will be evident from Figs. 4, 5, 6, 8, 9, and 10, the slow-wave structure 40 is the electrical equivalent of at least one helical conductor. Waveguide segments 42 and 44 are positioned in contact with envelope 12. This will be better understood as herein-after explained in connection with Figs. 2 and 3.

Slow-wave structure 40 comprises a plurality of coaxial conductive rings 41, one set of adjacent pairs of rings being connected at one arcuate portion 57 and the alternate set of pairs being connected to a portion 58 diametrically opposite portion 57. Waveguide segments 42 and 44 have transverse end portions 43 and 54, respectively, which have facing apertures 53 and 55 respectively, for launching a traveling-wave and for decoupling the wave at the output end of the slow-wave structure 40.

An external input waveguide segment 59 and an external output waveguide segment 60 are supported by suitable apertures in a disc-shaped dielectric spacer 49 which is disposed concentrically within the right end of envelope 12 adjacent a magnetic pole piece 180. Each of the external waveguide segments 59 and 60 are provided at their outer ends with mica "windows" 62 and 63, respectively, which provide vacuum seals. A vacuum is thus maintained from the "windows" 62 and 63 to the opposite end of envelope 12 at the extreme left of glass stem 36.

The stream electrons are intercepted by a collector electrode 52 at the opposite extremity of envelope 12 with respect to electron gun 14. Collector 52, which protrudes outside of the envelope 12, is also supported by a suitable aperture in dielectric spacer 49 so as to have a large surface external to the evacuated chamber for heat dissipation purposes and may include fins as shown to aid in conducting away the heat that is generated by the stream electrons when they are collected. Accordingly, collector 52 is preferably fabricated of a metal having good electrical and heat conducting properties, as in the case of structure 40, such as, for example, copper. A potential of the order of 200 volts positive with respect to structure 40 is applied to collector 52 in order to prevent secondary electrons which may be produced by the stream electrons impinging upon its surface from reaching slow-wave structure 40. This potential is applied by means of a connection from collector 52 to the positive terminal of a source 56, the negative terminal of which is grounded.

A plurality of conductive fins 51 are connected electrically and mechanically lengthwise of and from slow-wave structure 40 to a conductive cylinder 64 disposed within envelope 12. The conductive cylinder 64 is then mechanically and electrically connected to internal input waveguide segment 42 in order that heat may be con-

ducted from slow-wave structure 40 through conductive fins 51, conductive cylinder 64 and internal input waveguide segment 42 to envelope 12. This is better illustrated in Figs. 2 and 3 where solenoid 16, tank 19 and envelope 12 are respectively shown disposed concentric with one another. Internal input waveguide segment 42 is shown to be in contact with envelope 12 at two edges 66 and 68 in both Figs. 2 and 3 and in contact with conductive cylinder 64 at a point 70. In Fig. 2 a vertical fin 51 is shown connected to conductive cylinder 64 and to an axial conductor 72 of the conductive portion 57 connecting an adjacent pair of the conductive rings 41. In Fig. 3 two vertical fins 51, 51 are shown connected between a particular conductive ring 78 of the conductive rings 41 and conductive cylinder 64.

Fins 51 are shown to be in the same angular position in Fig. 1 although it is their axial positions or periodicity with respect to slow-wave structure 40 that makes them useful and not their particular arcuate positions. Each of the fins 51 has an arcuate thickness small in comparison to the external circumference of slow-wave structure 40 and extends axially over two of the cylinders 41 as clearly shown in Fig. 1. Each of the fins extends radially from the slow-wave structure 40 a distance equal to

$$\frac{n\lambda_0}{4}$$

where n is any positive odd integer and λ_0 is the free space wavelength corresponding to the mid-frequency of the operating band for which the tube 10 is designed. This requirement is made in order to avoid changing the impedance of the slow-wave structure in the center of the operating band, and very little about the center. When the fins 51 extend the above specified distance from slow-wave structure 40, a virtual shorting plane produced by conductive cylinder 64 will be prevented from appearing at the periphery of the slow-wave structure 40 between adjacent rings 41 to short electromagnetic energy therebetween. Wave propagation at the band center will thus be essentially the same with or without the use of fins 51.

The operation of the traveling-wave tube 10 is substantially the same as that explained in the previously mentioned sole application of Birdsall. Thus in the device 45 explained in that application and in the traveling-wave tube of the present invention an input signal to be amplified is impressed upon the input waveguide. A traveling wave is then launched on the slow-wave structure permitting interaction of the traveling wave with the electron stream projected from the electron gun. This interaction results in a transfer of energy from the electron stream to the wave causing the wave to "grow" or increase in amplitude as it progresses along the slow-wave structure. The amplified wave energy is then coupled from the output waveguide segment to a utilization device.

Fig. 4 is a broken orthogonal view of slow-wave structure 40, fins 51 and conductive cylinder 64. Fins 51 are shown with a maximum axial length in order to provide a maximum heat conducting cross section. Fins 51 can be made much shorter axially, but they can be made no longer because the desirable wave propagation properties of the slow-wave structure 40 would then be lost. The slow-wave structure 40 is thus seen to be the electrical equivalent of at least one helical conductor and in fact as illustrated in Fig. 4 is deemed to simulate unifilar contrawound helices having a finite pitch equal to a dimension 140. This is described in detail in the sole application of Birdsall referred to above. It is well known that periodic discontinuities along a waveguide structure, such as the fins 51 along the slow-wave structure 40, provide stop bands when they occur at a spacing or interval, L , equal to

$$\frac{m\lambda_0}{2}$$

where λ_g is the unloaded waveguide wavelength of the stop band mid-frequency and m is any positive integer. It is obvious that there is an upper and lower fin 51 disposed along the slow-wave structure 40 per pitch length in Fig. 4. Heat conduction nevertheless may be provided with fins on only one side of the slow-wave structure 40. This is illustrated in Fig. 5.

An alternative embodiment of the slow-wave structure of the present invention is shown in Figs. 6 and 7 where alternate pairs of adjacent conductive rings 41 are connected at diametrically opposed points by a plurality of conductive sheets 200 which extend tangentially from the rings 41 to conductive cylinder 64 in parallel planes. By the conductive sheets 200, heat may be efficiently conducted away from the conductive rings 41.

An additional embodiment of the slow-wave structure of the present invention is shown in Fig. 8 comprising a serpentine conductive strip 300 folded upon itself and having a plurality of registering apertures 302 therein to permit passage of an electron stream therethrough. A plurality of conductive columns or stubs 303 are then connected from the strip 300 to a conductive cylinder 304 which is positioned about the stubs 303 for heat conduction purposes. The slow-wave structure of Fig. 8 is electrically equivalent to that of Fig. 4 and hence the electrical equivalent of at least one conductive helix, the principal change in structure being in the angular width of the axially conductive segments 57, 58 and conductive fins 51. Planar transverse segments 306 of the conductive strip 300 are equivalent to conductive rings 41 and conductive fins 51 are represented by the plurality of radially conductive stubs 303.

In Fig. 9 a somewhat different slow-wave structure 142 is shown with conductive fins 144 connected thereto from a broken-away conductive cylinder 146. The slow-wave structure 142 is provided with straight axial segments 148 and 149 which connect alternate adjacent pairs of registering conductive rings 150 at diametrically opposed points. The axially straight conductive segments 148 are then positioned 90 degrees apart from the axially straight conductive segments 149. The slow-wave structure 142 thus provides a path which is electrically equivalent to at least one helical conductor and as shown simulates bifilar contrawound helices having a pitch indicated by dimension 152. This is likewise described in the sole application of Birdsall referred to above. As in the case of the loading of the slow-wave structure 40 in Fig. 4 slow-wave structure 142 in Fig. 9 is loaded twice per pitch. If the nature of the slow-wave structure 142 is closely considered, it is obvious that if one or more of the axially straight conductive segments 148 and 149 have conductive fins 144 extending thereto, the simulated contrawound helices of the slow-wave structure 142 may be loaded four, six, or eight times per pitch length.

In Fig. 10 a conventional type of conductive helix 170 for a traveling-wave tube is illustrated having a plurality of radially conductive fins 172 extending in one direction only and which have their radial extremities connected by a conductive cylinder 174. The helix 170 may be constructed in the form of a tape or wire, although a tape may have better heat dissipation capabilities.

In traveling-wave tubes employing unifilar and multifilar conductive helices, backward wave self-oscillations are troublesome. About the backward wave self-oscillation band, the practical operation of a traveling-wave tube solely as an amplifier is impossible. Conductive fins 172 may thus be employed to achieve two objectives. Firstly, conductive fins 172 may, as in the case of conductive fins 51, be used to conduct heat from helix 170 to conductive cylinder 174. Secondly, conductive fins 172 may in addition be employed to provide a stop band at the backward wave self-oscillation band of frequencies for the helix 170. The angular alignment of the conductive fins shown

in Fig. 10 is, of course, unnecessary although the relationship

$$d = \frac{m\lambda_g}{2}$$

should be maintained, where d is the axial spacing of the conductive fins 172 and λ_g is the unloaded guide wavelength at the mid-frequency of the backward wave self-oscillation band. The radial length of the conductive fins 172 may be

$$\frac{n\lambda_0}{4}$$

in accordance with the rule of design set down with respect to the radial length of the conductive fins 51 shown in Fig. 1. The axial length of conductive fins 172 may be equal to the width of the tape forming the helix 170. This is analogous to the case of the axial length of conductive fins 51 which have an axial dimension equal to the axially conductive length of the specified portions of the slow-wave structure 40 to which fins 51 are connected, i. e., equal to the sum of the width of two of the conductive rings 41 and the length of an axially conductive segment connecting two adjacent rings 41.

By the use of any of the embodiments of the device of the present invention stop bands may be provided or avoided as desired and heat may be conducted from traveling-wave tube slow-wave structures without reducing their forward wave impedances or their impedances to waves within their respective operating frequency bands.

What is claimed is:

1. A wave-type amplifier comprising an evacuated envelope, an electron gun disposed at one end of said envelope for producing an electron stream, a collector electrode disposed at the opposite end of said envelope to intercept the stream electrons, means for directing said electron stream along a predetermined path from said electron gun to said collector electrode, a conductive slow-wave structure for propagating electromagnetic waves within a predetermined frequency band having a mid-frequency corresponding to a free space wavelength of λ_0 , said slow-wave structure including a plurality of axially spaced conductive rings disposed concentrically about said path, and means electrically interconnecting adjacent rings alternately at diametrically opposed points; a plurality of conductive fins, each of said conductive fins extending axially over two adjacent conductive rings in electrical contact therewith at the arcuate position of at least one of said points, said conductive fins extending radially from said conductive rings a distance substantially equal to

$$\frac{n\lambda_0}{4}$$

where n is a positive odd integer, and a conductive cylinder disposed about said conductive fins, the outer extremities of said conductive fins being in physical and electrical contact with said conductive cylinder, whereby heat may be conducted away from said slow-wave structure without materially reducing the impedance of said slow-wave structure to waves of frequencies within said predetermined band.

2. A wave-type amplifier comprising an evacuated envelope; an electron gun disposed at one end of said envelope for producing an electron stream; a collector electrode disposed at the opposite end of said envelope to intercept the stream electrons; means for directing said stream along a predetermined path from said electron gun to said collector electrode; a slow-wave structure disposed contiguously about said path for propagating waves within a predetermined frequency band having a mid-frequency corresponding to a free space wavelength of λ_0 , said slow-wave structure including a plurality of axially spaced conductive cylinders disposed concentri-

cally about said path, and means electrically interconnecting adjacent cylinders at a pair of diametrically opposed points, consecutive pairs of said diametrically opposed points being displaced 90 angular degrees with respect to each other about said path; a plurality of conductive fins, each of said conductive fins extending axially over two adjacent conductive cylinders in electrical contact therewith at the arcuate position of at least one of said points, said conductive fins extending radially from said conductive cylinders a distance substantially equal to

$$\frac{n\lambda_0}{4}$$

where n is any positive odd integer; and conductive means connecting the outer extremities of said conductive fins, whereby heat may be conducted away from said slow-wave structure without materially reducing the impedance of said slow-wave structure to waves of frequencies within said predetermined band.

3. In a traveling-wave tube, an integral slow-wave structure and slow-wave structure support for propagating electromagnetic waves within a predetermined frequency band having a mid-frequency corresponding to a free space wavelength of λ_0 comprising a serpentine conductive strip including a plurality of parallel transverse segments having registering apertures and a plurality of axially conductive segments connecting adjacent pairs of said transverse segments alternately at their opposite ends, a conductive cylinder spaced

$$\frac{n\lambda_0}{4}$$

from the slow-wave structure, where n is any positive odd integer and λ_0 is the free space wavelength of the mid-frequency of the operating band of said amplifier, and a plurality of conductive stubs connected radially from said axially conductive segments to said conductive cylinder having an effective length substantially equal to

$$\frac{n\lambda_0}{4}$$

where n is any positive integer.

4. A wave-type amplifier comprising an evacuated envelope, an electron gun disposed at one end of said envelope for producing an electron stream, a collector electrode disposed at the opposite end of said envelope to intercept the stream electrons, means for directing said electron stream along a predetermined path from said electron gun to said collector electrode, a conductive slow-wave structure for propagating electromagnetic waves within a predetermined frequency band having a mid-frequency corresponding to a free space wavelength of λ_0 , said slow-wave structure including a plurality of axially spaced conductive rings disposed concentrically about said path, and means electrically interconnecting adjacent rings alternately at diametrically opposed points; a plurality of conductive fins having an arcuate thickness small in comparison to the circumference of said slow-

wave structure, each of said conductive fins extending axially over two adjacent conductive rings in electrical contact therewith at the arcuate position of each one of said points, said conductive fins extending radially from said conductive rings a distance substantially equal to

$$\frac{n\lambda_0}{4}$$

10 where n is a positive odd integer, and a conductive cylinder disposed about said conductive fins, the outer extremities of said conductive fins being in physical and electrical contact with said conductive cylinder, whereby heat may be conducted away from said slow-wave structure without materially reducing the impedance of said slow-wave structure to waves of frequencies within said predetermined band.

5. A wave-type amplifier comprising an evacuated envelope; an electron gun disposed at one end of said envelope for producing an electron stream; a collector electrode disposed at the opposite end of said envelope to intercept the stream electrons; means for directing said stream along a predetermined path from said electron gun to said collector electrode; a slow-wave structure disposed contiguously about said path for propagating waves within a predetermined frequency band having a mid-frequency corresponding to a free space wavelength of λ_0 , said slow-wave structure including a plurality of axially spaced conductive cylinders disposed concentrically about said path, and means electrically interconnecting adjacent cylinders at a pair of diametrically opposed points, consecutive pairs of said diametrically opposed points being displaced 90 angular degrees with respect to each other about said path; a plurality of conductive fins having an arcuate thickness small in comparison to the circumference of said slow-wave structure, each of said conductive fins extending axially over two adjacent conductive cylinders in electrical contact therewith at the arcuate position of each of said points, said conductive fins extending radially from said conductive cylinders a distance substantially equal to

$$\frac{n\lambda_0}{4}$$

45 where n is an positive odd integer; and conductive means connecting the outer extremities of said conductive fins, whereby heat may be conducted away from said slow-wave structure without materially reducing the impedance of said slow-wave structure to waves of frequencies within said predetermined band.
